UNITED STATES PATENT OFFICE.

ALFRED B. WALES, OF WHITMAN, MASSACHUSETTS, ASSIGNOR, BY MESNE ASSIGNMENTS, TO UNITED SHOE MACHINERY COMPANY, OF PATERSON, NEW JERSEY, A CORPORATION OF NEW JERSEY.

ART OF SHOEMAKING.

1,143,740.

Specification of Letters Patent. Patented June 22, 1915.

Application filed April 25, 1914. Serial No. 834,438.

To all whom it may concern:

Be it known that I, ALFRED B. WALES, a citizen of the United States, residing at Whitman, in the county of Plymouth and State of Massachusetts, have invented certain Improvements in the Art of Shoemaking, of which the following description, in connection with the accompanying drawings, is a specification, like reference characters on the drawing indicating like parts in the several figures.

This invention relates to improvements in the art of shoemaking and particularly to the manufacture of boots or shoes having blind eyelets.

What is termed a "blind eyelet" is an eyelet set in the lining or facing stay of a shoe upper beneath the leather or outer portion of the upper and in register with a hole through the latter portion which permits the passage of the lacing. The term is also employed to designate an eyelet set in the outer portion of an upper above the hole in the facing stay.

Heretofore, so far as known to me, in the setting of blind eyelets both the leather and the lining parts of the upper are punched and after this operation has been completed the upper is removed from the punching machine and the leather portion turned back so that the eyelets may be set in the lining in a foot power eyeleting machine. This method entails a second handling of the stock which is a relatively slow operation and also objectionable in that the upper must be stretched somewhat to permit the proper location of the setting dies of the machine when inserting the endmost eyelets in the line.

In accordance with the present invention an improved method is contemplated whereby the punching and eyeleting operations may be carried out while the leather and lining portions of the upper are maintained in the normal relation which they occupy permanently in the finished shoe. This method obviates the necessity of turning back the leather portion and stretching the upper in the insertion of the blind eyelets, as by the method heretofore practised, and also greatly expedites the process of manufacturing the shoe and results in an important saving to the shoe manufacturer. In fact, it has been customary to allow an op-

erator twelve cents per dozen pair for inserting blind eyelets by the methods heretofore practised, whereas, by the method of my invention the cost to the manufacturer is reduced to two cents per dozen pair for labor.

In one of its aspects, the invention comprises the method which consists in securing together the two parts of an upper and then setting a series of blind eyelets therein by alternating the step of punching both parts of the upper and the step of inserting an eyelet through the lining part and clenching its barrel on the concealed surface of the lining, as distinguished from the method heretofore practised and above outlined in accordance with which all the holes of the series are punched before any of the eyelets are set.

In my prior application Serial No. 695,064, filed May 4, 1912, I have disclosed and claimed an eyeleting machine by which certain steps of my improved method may be carried out, but it should be understood that the practice of this novel method is not restricted to this or any particular eyeleting machine or eyelet setting tools but may be carried out by any devices whatsoever whereby it is possible to set blind eyelets in one of the two parts of an upper while that part occupies the same normal relation to the upper part of the upper which is maintained in a finished shoe.

In the accompanying drawing certain steps of my improved method are illustrated in connection with the machine of my application above noted.

In the drawing, Figure 1 is a plan view of the upsetting die; Fig. 2 is a view in elevation, partly in section, of the punching and inserting tools; Fig. 3 is a similar view showing the punch in the position which it occupies at the conclusion of the punching operation; Fig. 4 is a similar view showing the tools in the position occupied at the conclusion of the setting operation; Fig. 5 is a perspective view of the upper of an Oxford in which a few blind eyelets have been set in accordance with my improved method.

In practising the method of my invention in the manner herein disclosed the upper and lining which have been previously cut out are brought together with their upper edges in register and secured in this po-

sition by cement which has previously been applied to one part or the other. This operation is known as Bal turning and by it the leather and lining parts of the upper 5 are brought into that relation which they are to occupy permanently in the finished shoe. They are maintained by cement in this relation and are more permanently secured together by subsequent stitching operations.

10 The second step in the present method consists in perforating or punching entirely through both parts of the upper. The hole thus formed in the leather or outer portion 15 remains to be seen in the finished shoe while the blind eyelet is set in the hole formed in the lining portion with its flange inside the upper and the end of its barrel clenched on the inner or concealed surface 20 of the lining beneath the leather or outer part.

25 The third step of the present method consists in inserting the blind eyelet while the two parts of the upper are maintained in their normal position. As above stated this 25 may be effected by any tools suitable for the desired function.

30 I will now briefly describe the practice of my improved method when the eyelet inserting operation is effected by such a machine as that of my prior application and to this end the construction of the machine will first be explained.

35 Referring to the drawing, 2 is a part of plate formed from a relatively thin flexible sheet of metal. This plate has a wide shank portion adapted to be secured by means of screws 3 to the top of the work table 4 of an eyeleting machine. The plate 2 is slotted 40 for purposes of adjustment and is secured in place above a block 5 which serves to lift it above the work table and may act also as an edge gage. By this arrangement the lining in which the eyelets are to be set 45 is allowed to pass under the plate 2 while the outer part 7 of the upper may pass over the plate 2. The plate 2 is slotted at 8 to permit the passage of the punching member 11. The slot is of sufficient length so that 50 it will not interfere with the feeding movement of the punch and extends in the direction of the feed to and through the neck portion 10 of the part 2.

55 The part 2 is provided with a projecting portion 9, the neck 10 of said portion 9 being bent downwardly as shown in Fig. 2 so that the punch 11 when moving forward to feed the stock will pass out of the opening 8 and over the forward projection 60 9. On the under side of the projection 9 is secured an upsetting die or upper set member 12 which cooperates with the set 13 of the machine, and when the punch has completed its forward feed movement it is directly over the upper set 12 as shown in Fig. 65

4. The forward feed movement of the punch causes the neck portion of the part 2 to disengage the inner part 6, or lining, from the point of the punch, and the engagement of the punch with the outer part 7 of the stock 70 carries the leather forward until the upsetting die is located in the hole just formed by the punch in the lining. When the punch is in this position the under set 13 with the eyelet 14 in position as shown in 75 Figs. 1, 2 and 3 is moved upwardly and the eyelet is set in the lining part 6 as shown in Fig. 4. The part 2 together with its projecting end 9 may be made of comparatively thin sheet material, because at the time the 80 eyelet is set it is backed up by the punch and is therefore held rigidly and prevented from yielding. After the eyelet is set the punch moves upwardly and toward the right as seen in Fig. 4 and again descends through 85 the slot 8 cutting holes in both the upper and lower pieces 7 and 6 and again feeds the stock forward stopping directly over the upsetting die 12 on the projection 9, and another eyelet is then set in the lower strip 90 and the operation repeated. The construction and operation of the punch, as also the lower set, are well known to those skilled in the art and do not require detailed description. 95

100 In practising the method of the present invention, when the above described machine is employed, the upper is presented with the lining part 6 below the plate 10 and the leather or outer part 7 above the plate 10, the two parts being secured together by cement as indicated by reference character 20 in Fig. 5. The plate 10 is so shaped as to extend only a short distance within the edge of the upper so that the 105 two parts thereof remain in contact or closely adjacent to each other over substantially the entire area during the eyeleting operation. The insertion of the thin plate 10 at the edge of the upper in no way disturbs the normal relation of the parts which as already stated has been established and is maintained throughout the operation and in the finished shoe. The work is then punched and advanced to a position in 110 which the holes are in alignment with the under set 13 which is then elevated to insert an eyelet through the lining 6, while the hole in the leather part is held positively in alignment by the tool 11. The eyelet barrel 110 is met by the upsetting die 12 which clenches the barrel upon the lining entirely beneath the leather portion 7. These steps are then repeated until the number of eyelets required in the series has been set. 115

120 Having thus described my novel method and one suitable form of apparatus by which it may be carried into effect, I claim as new and desire to secure by Letters Patent:

1. In the manufacture of boots and shoes,

- the method of inserting blind eyelets which consists in perforating both the leather and the lining parts of a shoe upper by means of a punching tool, inserting an eyelet through the lining from the inside of the upper, and clenching the end of its barrel on the covered side of the lining beneath the leather part of the upper while the leather part is held by the punching tool which has been inserted therein and while the two parts of the upper occupy the same normal relation that is preserved in the finished shoe.
2. In the manufacture of boots and shoes, the method of inserting blind eyelets which consists in perforating both the leather and the lining parts of a shoe upper while said parts are held in their normal superposed relation, inserting an eyelet through the lining from the inside of the upper, and clenching the end of its barrel on the lining while the hole in the leather part is positively held in register with the eyelet and while the two parts of the upper are maintained in said normal relation and in contact over substantially their entire area.
3. In the manufacture of boots and shoes, that method which consists in securing together in normal relation the leather and lining parts of a shoe upper, perforating both parts, and setting an eyelet in one part in register with the hole in the other part, while the two parts of the upper are maintained in said normal relation and adjacent to each other and with the hole positively held in alinement with the eyelet during the setting operation.
4. In the manufacture of boots and shoes, that method which consists in securing together in normal relation the leather and lining parts of a shoe upper, perforating both parts, introducing an upsetting surface
- between the two parts, and thereafter inserting an eyelet through the lining part and clenching its barrel against the upsetting surface on the lining part and independently of the leather part and while the hole in the leather part is held positively in alinement with the eyelet being set.
5. In the manufacture of boots and shoes, the method of inserting blind eyelets which consists in securing together the lining and outer parts of an upper in that relation which they are to occupy in the finished shoe, perforating both parts by means of a punching tool, inserting an eyelet through the lining part from the inside of the upper, and clenching the end of the eyelet barrel on the concealed side of the lining beneath the outer part before the punching tool is withdrawn from the upper and while the two parts of the upper occupy their normal relation.
6. In the manufacture of boots and shoes, the method which consists in securing together the lining and outer parts of an upper in the normal relation which is to be preserved in the finished shoe, and setting a series of blind eyelets by alternating the step of punching both parts of the upper with the step of inserting an eyelet through the lining part only and clenching its barrel on the surface of the lining adjacent to the outer part, said steps being continued until the required number of blind eyelets has been set in the upper.

In testimony whereof I have signed my name to this specification in the presence of two subscribing witnesses.

ALFRED B. WALES.

Witnesses:

WILLIAM HUGHES,
HARRISON W. GEORGE.

It is hereby certified that in Letters Patent No. 1,143,740, granted June 22, 1915, upon the application of Alfred B. Wales, of Whitman, Massachusetts, for an improvement in "The Art of Shoemaking," an error appears in the printed specification requiring correction as follows: Page 2, line 90, for the words "lower strip" read *lining part*; and that the said Letters Patent should be read with this correction therein that the same may conform to the record of the case in the Patent Office.

Signed and sealed this 22d day of February, A. D., 1916.
